JOHN O'MAHONY, OF SAVANNAH, GEORGIA.

Letters Patent No. 77,810, dated April 28, 1868.

IMPROVEMENT IN DRAY-SADDLE.

The Schedule referred to in these Letters Patent and making part of the same.

TO ALL WHOM IT MAY CONCERN:

Be it known that I, JOHN O'MAHONY, of Savannah, in the county of Chatham, and State of Georgia, have invented a new and improved Dray-Saddle; and I do hereby declare that the following is a full, clear, and exact description thereof, which will enable others skilled in the art to make and use the same, reference being had to the accompanying drawings, forming part of this specification.

This invention consists in a novel construction of the saddle, whereby it may be made to conform to the shape of the back of the horse, and a very durable saddle of the kind specified obtained, and one which will not chafe or injure the horse in the least.

In the accompanying sheet of drawings—

Figure 1 is a side view of my invention.

Figure 2, a front view of the same.

Figure 3, a transverse section of a portion of the same, taken in the line x x, fig. 1.

Similar letters of reference indicate corresponding parts.

A represents the exterior portion of the saddle, which is constructed of heavy leather, elevated in front, very similar to a military riding-saddle.

B is a wooden grooved bar, secured to the outer side of A, and grooved longitudinally, to receive the chain which supports the thills of the dray.

To the under side of the leather, A, at each side of the same, there are secured bevelled blocks C C, one of which is shown clearly in fig. 3. These blocks are bevelled so as to increase in thickness from their upper edges downward. These bevelled blocks give a proper shape to the pads D, and cause the same to conform to the shape of the back of the horse, the pads D being secured over the blocks, and the latter keeping the former in proper shape, as will be fully understood by referring to fig. 3.

Pads for dray-saddles, when constructed in the best possible manner, soon get out of proper shape, they are subjected to so much weight; and this, in connection with the perspiration from the animal, causes the pads to flatten and become hard, so that they will injure the horse. The blocks C, however, retain the pads in proper shape, and render the saddle easy and comfortable for the horse until the former is entirely worn out.

I claim as new, and desire to secure by Letters Patent—

In a dray-saddle, the bevelled blocks C C, secured to the leather covering A, in combination with the pads D and grooved bar B, said blocks C being secured to the pads at their centres, for the purpose of preventing such pads from flattening upon the back of the animal, under the weight of the dray, as herein shown and described.

The above specification of my invention signed by me, this thirteenth day of September, 1867.

JOHN O'MAHONY.
